Charles R. Searle.

UNITED STATES PATENT OFFICE.

HERBERT A. DEKNATEL, OF NEW YORK, N. Y.

RUG-STIFFENER.

1,179,704.

Specification of Letters Patent. Patented Apr. 18, 1916.

Application filed May 19, 1915. Serial No. 29,050.

To all whom it may concern:

Be it known that I, HERBERT A. DEKNATEL, a citizen of the United States, residing in the city of New York, borough of Manhattan, in the county and State of New York, have invented a certain new and useful Improvement in Rug-Stiffeners, of which the following is a specification.

The invention relates to devices for stiffening the corners of rugs and analogous floor coverings to resist the tendency of such corners to curl upwardly, and thus avoid the dangers and the unsightly appearance due to such curling.

The object of the invention is to provide a simple stiffener of economical construction which may be easily and quickly applied and which will hold reliably and serve efficiently.

The invention consists in certain novel features and details of construction by which the above objects are attained, to be hereinafter described and claimed.

The accompanying drawings form part of this specification and show the invention as it has been carried out.

Figure 1 is a plan view of the under face of a rug-corner equipped with the invention in its complete form. Fig. 2 is a plan view of an angular stiffener adapted to follow the margins of a corner. Fig. 3 is a corresponding edge view. Fig. 4 is a plan view of a straight stiffener adapted to extend inwardly diagonally from the corner. Fig. 5 is an edge view corresponding to Fig. 4.

Similar letters of reference indicate the same parts in all the figures.

A is the corner of a rug which may be understood to be of the Brussels type having the usual foundation threads B showing on the reverse face. The material for the stiffeners is spring wire of the required resiliency and gage and is preferably cylindrical as best adapted, by reason of the absence of angular edges, to lie upon the floor without danger of defacing the latter, but which may be of any desired cross-sectional form.

In the complete form of the invention as illustrated in Fig. 1, the stiffener is in two portions, one having arms D D formed by bending the wire at a right angle at its midlength, adapted to apply upon the under face of the corner of the rug and follow the margins thereof for a short distance in

both directions, and a second relatively straight wire F adapted to be applied diagonally inward from the corner. At the junction of the arms D D the wire is bent to form an open loop D¹ lying in a plane parallel with the face of the rug, and near the sharpened extremities D² of the arms each of the latter is offset or bent into serpentine form as at D³, the offset or convolutions lying in the same plane as the loop D¹ so as to apply flatwise upon the under face of the rug. It is secured to the rug by engaging one of the arms D in one of the exposed loops B¹ of the foundation fabric at the corner and sliding such arm through such loop until the latter is approached by the open loop D¹, the point D² of the same arm is then engaged in a thread-loop B² and slipped therethrough and engaged in the first of a series of loops B³ B³ and thrust therethrough until the thread loop B¹ enters the bight of the open loop D¹ and engages the latter, and the loop B² engages the cross-bar of the serpentine bend D³, with the extremity of the arm lying in the thread loops B³ B³. The other arm D is similarly engaged by bending it upward sufficiently to permit the entrance and engagement of its point D² and serpentine bend D³ with the thread loops B² and B³ B³ and again allowed to straighten. Thus engaged the wire is held reliably and exerts its stiffness to resist yieldingly any tendency of the corner to curl.

The wire F serves as an angular reinforcement for the corner. It is sharpened at both ends, and near the point F¹ is a serpentine bend or offset F³ similar to that above described. The wire F is engaged by slipping the opposite point F² through several loops C C of the foundation threads far enough to permit the insertion of the point F¹ through a loop C², the wire is then slipped back in the reverse direction with the point F¹ engaging successive loops C¹ until the offset F³ reaches and is engaged by the loop C², and the point F¹ is engaged with the several loops C¹. Either wire may be employed without the other and will serve alone with a large measure of success, but the wire F when used alone, while effectually preventing curl transversely to itself, will not prevent the formation of wrinkles or waves alongside of or parallel with such wire; and the wire D D while holding the margins of the corner against

curling may permit wrinkles in the area between such margins and transversely to the diagonal line of the corner. Straight wires F may be inserted wherever desired; two or 5 more may be located in the margins of the rug at the corner to lie at a right angle to each other, and another similar wire inserted diagonally from such corner if desired. It 10 will be noted that in applying both or either wires they are reliably engaged without mutilating the rug and without requiring stitches to be taken to secure them in place, and they may be easily removed and replaced.

15 Although the invention is for convenience shown and described as applied to the relatively harsh under surface of a Brussels rug it will be understood that the wires may be similarly engaged with any fabric and in 20 rugs of softer texture will embed themselves in the material and thus further reduce the danger of defacing the floor.

I claim:

25 1. A rug stiffener comprising a single piece of wire pointed to enter the material of the rug and having means intermediate

its ends in the plane of and integral with such wire to engage opposite sides of a thread of the rug to resist withdrawal.

2. A rug stiffener formed of a single piece 30 of wire pointed at its ends and formed with a serpentine offset portion intermediate its ends, all portions thereof being disposed in the same plane.

3. A rug stiffener comprising a single 35 piece of wire having arms extended at a right angle to each other and pointed at the ends, an open loop at the junction of said arms and lying in the plane of the latter, and offset portions on each arm arranged to 40 lie in such plane, said pointed ends adapted to enter the material of the rug, and said loop and offsets adapted to engage with the threads of such rug to resist withdrawal.

In testimony that I claim the invention 45 above set forth I affix my signature, in presence of two witnesses.

HERBERT A. DEKNATEL
